BURNER

William A. Morton, Mount Lebanon, Pa., assignor, by mesne assignments, to Union Mining Company of Allegany County, Pittsburgh, Pa., a corporation of Maryland

Application November 12, 1942, Serial No. 465,296

6 Claims. (Cl. 153—76)

This invention relates to burners and more particularly to a burner structure having improved means for controlling the character of the burner flame. The invention relates still more particularly to a burner having a movable air guide for controlling in a novel manner the flow of air toward the burner outlet and thereby controlling the character of the flame.

Various means have heretofore been provided for controlling the character of flame produced by a burner. A burner flame may be a short quick-burning oxidizing flame or it may be a long slow-burning reducing or luminous flame depending upon the conditions imposed upon the fuel and air as they approach and reach the point of combustion. I provide improved and extremely simple and inexpensive means for controlling the character of a burner flame.

I provide a burner comprising a casing having separate fuel and air inlets and a combined fuel and air outlet and an air guide in the casing movable to one position in which it is operable to guide air from the air inlet toward the outlet generally parallel to the fuel passing toward the outlet and to another position in which it is operable to guide at least part of the air toward the outlet generally transversely to the fuel passing toward the outlet. When all or substantially all of the air passing toward the outlet flows generally parallel to the fuel passing toward the outlet so that the air and fuel come in contact adjacent the outlet with little turbulence the resultant flame is a long slow-burning reducing or luminous flame. When, however, a substantial portion of the air passing toward the outlet flows generally transversely to the fuel passing toward the outlet the result is an admixture of such air and fuel with considerable turbulence, resulting in a relatively short quick-burning oxidizing flame.

I preferably mount the air guide so as to be movable generally toward and away from the outlet. Preferably the air guide has one or more air passages therein extending generally parallel to the direction of flow of the fuel passing toward the outlet and normally at least some of the air from the air inlet passes through such passage or passages in the air guide on its way toward the outlet. Preferably the forward end or nose of the air guide is adapted to contact with the casing about the outlet so that when the air guide is in its extreme forward position with its nose in contact with the casing about the outlet no air can pass from the air inlet to the outlet externally of the air guide between the nose of the air guide and the immediately adjacent portion of the cas-

ing. When, however, the air guide is somewhat retracted so that air may pass from the air inlet externally of the air guide between the nose of the air guide and the immediately adjacent portion of the casing toward the outlet and into contact with the fuel adjacent the outlet, such air, impinging against the stream of fuel at a substantial angle thereto, creates a turbulent condition resulting in a short quick-burning oxidizing flame.

I also provide means for adapting in an extremely simple manner a burner primarily intended for burning gas for use as a liquid fuel burner. I preferably provide an air guide slidably toward and away from the burner outlet and having a bore of such size as to receive with a sliding fit a gas nozzle. When the burner is to be used for liquid fuel I apply a liquid fuel atomizer and nozzle, the liquid fuel nozzle extending within the bore of the air guide and carrying externally a member having about the same outside dimensions as a gas nozzle adapted to have a sliding fit with said bore. Also the fuel inlet of the casing is preferably of such size as to receive a gas nozzle and means are preferably provided when the burner is to be used for liquid fuel for closing the fuel inlet about the liquid fuel atomizer and nozzle. Thus with very minor inexpensive changes the burner may be transformed from a gas burner into a liquid fuel burner.

Other details, objects and advantages of the invention will become apparent as the following description of certain present preferred embodiments of the invention proceeds.

In the accompanying drawings I have shown certain present preferred embodiments of the invention, in which

Figure 1 is an end elevational view of a burner;
Figure 2 is a central vertical longitudinal cross-sectional view of the burner shown in Figure 1 taken on the line II—II of Figure 1;

Figure 3 is a view similar to Figure 2 showing a modified construction; and

Figure 4 is a vertical transverse cross-sectional view of the structure shown in Figure 3 taken on the line IV—IV of that figure.

Referring now more particularly to Figures 1 and 2, there is provided a burner having a casing 2 having an air inlet 3, a fuel inlet 4 and a combined fuel and air outlet 5. In the form shown the fuel inlet 4 is coaxial with the outlet 5. There is provided a fuel duct which in the form shown in Figures 1 and 2 is a gas nozzle designated by reference numeral 6. The outside diameter of the gas nozzle 6 is such that the

nozzle fits snugly within and substantially seals the fuel inlet 4 of the casing 2. A set screw 7 in the casing is adapted to bear upon the nozzle 6 to maintain it in desired adjusted position relatively to the casing. The nozzle may be adjusted axially relatively to the casing as indicated by the chain lines in Figure 2.

There is provided an air guide 8 which is disposed within the casing 2 and is slideable toward and away from the outlet 5. The air guide 8 is mounted upon and slideable relatively to the gas nozzle 6 as shown in Figure 2. It has a bore 9 of such size as to form a sliding fit with the outside of the nozzle 6. The air guide 8 also has a series of air passages 10 disposed generally about the nozzle 6 as shown in Figure 1 and adapted to guide air toward the outlet 5 in a direction generally parallel to the axis of the nozzle 6 and hence generally parallel to the fuel flowing toward the outlet.

The air guide 8 also has a frusto-conical nose portion 11 adapted when the air guide is in the extreme forward or left-hand position as shown in Figure 2 to contact and substantially seal against a seat 12 formed internally of the casing 2 about the outlet 5. A bolt 13 passes through a bore 14 in the casing 2 and has a reduced inner end 15 entering a bore 16 in a web portion 17 of the air guide 8. A nut 18 is disposed within an opening 19 in the air guide and threaded upon the reduced end 15 of the bolt 13 so that longitudinal movement of the bolt 13 results in similar movement of the air guide 8. The bolt, and hence the air guide, is maintained in desired adjusted positions by a set screw 20 functioning similarly to the set screw 7 above described.

The burner is adapted to be applied to any appropriate furnace, a furnace burner opening being indicated at 21 in Figure 2. When it is desired to provide a long slow-burning reducing or luminous flame the air guide 8 is moved to the extreme left-hand position as shown in Figure 2 where its conical nose 11 seats against the seat 12 of the casing. When the air guide is in this position all of the air entering through the air inlet 3 passes downwardly and to the right viewing Figure 2 and thence from right to left through the air passages 10 in the air guide 8 toward the outlet 5. When the air guide is in such position the air passing toward the outlet flows substantially parallel to the fuel passing toward the outlet so that the air and fuel mix with little turbulence, resulting in a long slow-burning reducing or luminous flame. When, however, a relatively short quick-burning oxidizing flame is desired the air guide 8 is retracted from the position shown in full lines in Figure 2 to another position, as, for example, that indicated by dotted lines in Figure 2. With the air guide thus positioned part of the air entering the casing through the air inlet 3 flows, as above described, through the air passages 10 while another part of the air flows through the passage formed between the nose 11 of the air guide and the seat 12 of the casing. Such nose 11 and seat 12 form an air passage which directs the air passing therethrough toward the outlet 5 in a direction generally transversely to the fuel passing toward the outlet through the nozzle 6. Such air impinges on the stream of fuel (and such air as passes through the passages 10) in such manner as to create substantial turbulence adjacent the ignition point, resulting in a relatively short quick-burning oxidizing flame. The character of the flame can be controlled by positioning the air guide 8 in various positions

axially of the nozzle 6, this being done by loosening the set screw 20 and moving the air guide by pulling or pushing the outer end of the bolt 13 and then tightening the set screw 20. The gas nozzle 6 may be similarly adjusted but ordinarily the nozzle is initially adjusted and then left in a preferred position. It is possible by fully retracting the air guide 8 to cause all the air which enters through the air inlet 3 to pass through the passageway between the nose 11 of the air guide and the seat 12 of the casing, but it will seldom if ever be desired to do this. Ordinarily at least a portion of the air will pass through the passages 10 in the air guide.

The structure shown in Figures 3 and 4 is the same as that shown in Figures 1 and 2 except that in Figures 3 and 4 such structure has been adapted for the burning of liquid fuel, as, for example, oil. The gas nozzle 6 of Figures 1 and 2 has been removed and in its place there is shown in Figure 3 a liquid fuel atomizer 22 and nozzle 23. The liquid fuel atomizer and nozzle are of considerably smaller outside dimensions than the gas nozzle 6. Disposed about the atomizer 22 is a ring 24 adapted to fit and close the fuel inlet 4. The ring 24, together with the liquid fuel atomizer and nozzle carried thereby are adapted to be held in desired adjusted position by the set screw 7 in the same manner as such set screw acts on the gas nozzle 6 in the structure shown in Figure 2. A set screw 25 is adapted to hold the ring 24 in place about the atomizer, such set screw of course being tightened before the atomizer 22, nozzle 23 and ring 24 are introduced into the fuel inlet 4.

The liquid fuel nozzle 23 carries externally a member 26 having about the same outside diameter as the gas nozzle 6 of Figure 2 and adapted to have a sliding fit with the bore 9 of the air guide 8. The member 26 prevents the passage of air through the bore 9 of the air guide and assists in guiding the air guide within the casing. The member 26 is held in desired adjusted position on the nozzle 23 by a set screw 27.

No novelty is claimed for the specific form of atomizer and liquid fuel nozzle and these may be of standard construction. The liquid fuel may enter through a pipe 28 and the atomizing fluid through a pipe 29, the atomizing function being accomplished in well known manner.

The structure of Figures 3 and 4 operates in the same manner as that of Figures 1 and 2 so far as control of the air flow by the air guide 8 is concerned and the above description of the control of the air flow by the structure of Figures 1 and 2 applies also to the structure of Figures 3 and 4. Thus I have provided a burner of extremely simple and inexpensive construction which functions in an improved manner to control the character of the flame and which can very simply and easily be converted from a gas burner to a liquid fuel burner and vice versa.

While I have shown and described certain present preferred embodiments of the invention it is to be distinctly understood that the invention is not limited thereto but may be otherwise variously embodied within the scope of the following claims.

I claim:

1. A burner comprising a casing having separate fuel and air inlets and a combined fuel and air outlet, a fuel duct within which fuel is adapted to flow from the fuel inlet toward the outlet and an air guide surrounding the fuel duct and movable generally toward and away from the outlet,

said guide having a series of passages disposed about the fuel duct and generally parallel thereto for guiding air from the air inlet toward the outlet and also having a nose portion adapted when the guide is in one position to contact the casing to prevent flow of air therebetween and adapted when the guide is in another position to form with the casing a passageway extending at an angle to the axis of the fuel duct for passage of air from the air inlet toward the outlet.

2. A burner comprising a casing having separate fuel and air inlets and a combined fuel and air outlet, an air guide slidable toward and away from the outlet, the air guide having a bore and air passage means generally parallel to the bore, a ring disposed within the fuel inlet adapted to receive and embrace a liquid fuel atomizer and nozzle with the nozzle extending within the bore of the air guide and a member adapted to embrace the nozzle and having a sliding fit within said bore.

3. A burner comprising a casing having separate fuel and air inlets and a combined fuel and air outlet, a fuel duct within which fuel is adapted to flow from the fuel inlet toward the outlet and an air guide having an opening within which the fuel duct passes and movable generally toward and away from the outlet, said guide having means separate from said opening for guiding air from the air inlet toward the outlet generally parallel to the fuel duct, the end of said guide nearer the outlet being adapted when the guide is in one position to contact the casing to prevent substantial flow of air between the casing and said end of the guide and adapted when the guide is in another position to be spaced from the casing to permit flow of air between the casing and said end of the guide toward the outlet.

4. A burner comprising a casing having separate fuel and air inlets and a combined fuel and air outlet, an air guide slidable toward and away from the outlet, the air guide having a bore and air passage means generally parallel to the bore, a liquid fuel atomizer and nozzle, a ring disposed within the fuel inlet for receiving and embracing the liquid fuel atomizer and nozzle with the nozzle extending within the bore of the air guide and a guiding member disposed about the nozzle within the bore of the air guide for relatively guiding the air guide and nozzle.

5. A burner comprising a casing having separate fuel and air inlets and a combined fuel and air outlet, a fuel duct within which fuel is adapted to flow from the fuel inlet toward the outlet and an air guide having an opening within which the fuel duct passes and movable generally toward and away from the outlet, said guide having means separate from said opening for guiding air from the air inlet toward the outlet generally parallel to the fuel duct, the end of said guide nearer the outlet being adapted when the guide is in one position to contact the casing to prevent substantial flow of air between the casing and said end of the guide and adapted when the guide is in another position to be spaced from the casing to permit flow of air between the casing and said end of the guide toward the outlet, said guiding means being of such length in the direction generally parallel to the fuel duct that when said end of the guide is in contact with or close to the casing air is delivered therefrom with little turbulence and a long luminous flame is produced whereas when said end of the guide is spaced a considerable distance from the casing the air flowing between the casing and said end of the guide toward the outlet and meeting the fuel or fuel and air flowing toward the outlet creates a relatively turbulent condition resulting in a short non-luminous flame.

6. A burner comprising a casing having separate fuel and air inlets and a combined fuel and air outlet, a fuel duct within which fuel is adapted to flow from the fuel inlet toward the outlet and an air guide having an opening within which the fuel duct passes and movable generally toward and away from the outlet, said guide having means separate from said opening for guiding air from the air inlet toward the outlet generally parallel to the fuel duct, the end of said guide nearer the outlet being adapted when the guide is in one position to contact the casing to prevent substantial flow of air between the casing and said end of the guide and adapted when the guide is in another position to be spaced from the casing to permit flow of air between the casing and said end of the guide toward the outlet, the fuel duct being positionable with its delivery end at various predetermined distances from the outlet.
